UNITED STATES PATENT OFFICE.

FRANK KALMAN, OF SYDNEY, NEW SOUTH WALES, AUSTRALIA.

TROUSERS.

1,418,578.

Specification of Letters Patent. Patented June 6, 1922.

Application filed December 23, 1920. Serial No. 432,811.

To all whom it may concern:

Be it known that I, FRANK KALMAN, subject of the King of Great Britain and Ireland, residing at 80 Bathurst Street, Sydney, 5 in the State of New South Wales, Commonwealth of Australia, have invented new and useful Improvements in Trousers, of which the following is a specification.

This invention relates to men's trousers 10 and has particular reference to means by which the trousers are held in position around the waist of the wearer.

The object of the invention is to provide a simple and efficient means whereby the 15 trousers are held in position around the waist of the wearer without the use of braces or belt and at the same time to provide means whereby the circumferential length around the waist will be automatically increased or decreased according to the expansion or contraction of the body of the wearer.

To effect the object in view the trousers are provided with a loose vertical pleat situated at each side of the trousers, preferably immediately behind the side seams. These pleats are so formed as to gradually diminish to zero at or near the bottom of the side pocket openings. The innermost face 25 of each of these pleats is secured by means of stitching or by a button to one end of a rearwardly extending strip of elastic webbing, the other ends of such webbing being secured at points about midway between the 30 side seams and the centre of the back, while the outermost face of each pleat is secured in a similar manner to a strip of elastic webbing which extends thence forwardly, the other end of each strip being secured 35 at a point about midway between the seams and the centre of the front portion of the trousers. The foremost ends of the strips of webbing which extend forwardly are passed through 40 openings made in the side seams and from thence along the inside front of the trousers to the point at which they are attached. Any or all of these strips of webbing may 45 pass into and along "tubes" or "casings" 50 which are formed by two parallel lines of stitching securing the lining to the material of which the trousers are made. This se-

cures the webbing to the trousers along practically its entire length and at the same time prevents it from rubbing against the 55 inner clothing of the wearer.

In a modification, the rearwardly extending webbing consists of one strip instead of two, one end of this strip being stitched to a tab provided with a button hole engaging with a button upon the innermost face of the pleat on the right hand side and passing thence through a "tube" or "casing" formed across the inside rear waist of the trousers, to the left hand side where the 60 other end of the webbing is similarly secured to the innermost face of the pleat on that side.

The application of the invention will be more readily understood by referring to the 70 accompanying sheet of drawings in which:—

Fig. 1 illustrates one method of applying the invention, the figure being a perspective view of the waist portion of a pair of trousers with the lining removed. 75

Fig. 2 is a section taken on the line A. A. of Fig. 1 with the lining in position.

Fig. 3 shows that portion of the back part of the trousers in which the triangular piece of webbing is inserted, while, 80

Fig. 4 illustrates another method of applying the invention the figure being the waist portion of a pair of trousers with the lining removed.

Before entering into the detailed description of these drawings attention is called to the fact that there are many different methods by which my invention may be put into practical use and those herein described have been chosen as the most suitable for the 90 purpose of describing and illustrating how the invention is to be applied.

Referring now more particularly to Fig. 1. The pleats 6 are placed preferably one at each side of the trousers Z immediately to 95 the rear of the side seams 7 so that they may be made to taper off to zero at or near the bottom of the pocket openings 8. The outermost surface 9 of these pleats is provided with a button 10 that engages with a button hole 11 in a tab 12 secured to one end of a strip of elastic webbing 13. This elastic webbing is passed inwardly through an opening 14 in the seam 7 of the trousers, into

and along a "tube" or "casing" formed by placing a piece of lining upon the inner surface of the trousers and securing them together by means of two parallel lines of stitching. This tube or casing extends from a point 15 in front of the seam to a point 16 about midway between the seam and the middle front of the trousers. The end of the webbing most remote from the pleat will be firmly secured to the material by stitching 17 or it may be provided with a tab and button hole to engage with a button secured upon the inside of the trousers as shown at 17^a in Fig. 4. A strip of elastic webbing 20 is similarly secured at 19 to the innermost face 18 of each pleat, but this piece will extend from the pleat rearwardly to a point 21 about midway between the pleat and the centre of the back of the trousers where it will be securely fastened by means of stitching or by a button and button hole as previously explained.

Referring now to Fig. 3, a portion of the trouser material in the centre of the back is cut away and a triangular piece of elastic webbing 22 inserted and secured by stitching 23 in a manner that will be readily understood.

The modification consists of the substitution of one piece of elastic webbing 24 for the two rearwardly extending pieces 20. This modification makes the inserted triangular piece 22 unnecessary, reduces the cost of manufacture and incidentally all these pieces of webbing may be quickly removed or replaced as required.

Fig. 4 shows the modification, the ends of the webbing 24 being provided with tabs 25 in each of which are button holes that engage with button 26 upon the innermost face of the pleat 6, and extend rearwardly from pleat to pleat. This webbing 24 will pass through a tube or casing extending approximately from the point 27 to the point 28.

Although in Figs. 1 and 4 the tube or casing, which is partly formed by the lining, is not shown it will be readily understood by referring to Fig. 2 in which 29 is the outer surface of the trouser material, 13 the lining, 31 the elastic webbing, 32 and 33 the two parallel lines of stitching securing the lining to the trouser material.

In operation the expansion of the body of the wearer will cause the trousers to expand by opening out the pleats 6 and extending the elastic webbing 13 and 20, or 13 and 24. In this extended position the elastic webbing 13 is pulling in the opposite direction to either the elastic webbing 20 or 24 as the case may be, so that pressure is maintained around the waist of the wearer until contraction of the body takes place, when, as the strain upon the elastic webbings 13 and 20 or 24 is released they will gradually

contract and in doing so will automatically carry the pleats 6 with them and cause the latter to assume their normal size.

From the nature of this invention it will be clearly seen that although it has been described with special reference to trousers, it is equally applicable to other wearing apparel, but more particularly to that class which hangs from the waist.

I claim:—

1. In a garment which encircles a portion of the human body, a plait having a substantially Z-shaped cross-section, an elastic strip having one of its ends secured to the garment and its other end secured to the inner surface of said plait, and a second elastic strip having one of its ends secured to the garment and its other end secured to the opposite surface of the plait, said strips being adapted to yieldingly maintain the substantially Z-shaped plait in the garment.

2. In a garment which encircles a portion of the human body, a substantially V-shaped plait having a substantially Z-shaped cross-section, an elastic strip having one of its ends secured to the garment and its other end secured to the inner surface of said plait, and a second elastic strip having one of its ends secured to said garment and its other end secured to the opposite side of said plait at a point arranged between the points of connection of said first mentioned strip, said strips being adapted to exert a pulling action in opposite directions on said plait and to normally maintain the plait in folded condition.

3. In a garment which encircles a portion of the human body, a substantially V-shaped plait having a substantially Z-shaped cross-section and provided with an opening, an elastic strip having one of its ends secured to the inner surface of the garment and its other end portion passed through said opening and secured to the outer surface of said plait, and a second elastic strip having one of its ends secured to the inner surface of the garment and its other end secured to the inner surface of the plait.

4. A garment having a waist band portion, plaits arranged at the sides of said garment and openings passing through the opposite sides of the garment, elastic strips having their inner ends secured to the inner surfaces of the front portion of the garment and having their other end portions extended through said openings and secured to the outer surfaces of the plaits, and other elastic strips having their rear ends connected to the rear portion of the garment and their forward ends secured to the inner surfaces of said plaits.

5. A garment of the kind defined by claim 4 in which the first mentioned elastic strips are secured to the front of the garment by detachable connections.

6. A garment of the kind defined by claim 4 in which the ends of the first mentioned strips which extend through said openings are connected to the outer surfaces of the garment by detachable connections.

7. A garment of the kind defined by claim 4 in which the second mentioned strips are connected together.

8. A garment of the kind defined by claim

4 in which the second mentioned strips are 10 connected to the inner surfaces of said plaits by detachable connections.

9. A garment of the kind defined by claim 4 in which linings are arranged in the inner surfaces of said garment to cover said strips. 15

In testimony whereof I have signed my name to this specification.

FRANK KALMAN.
